UNITED STATES PATENT OFFICE.

JOHN FREDERICK CHRISTIAN DEHLE, OF SACRAMENTO, CALIFORNIA.

DESIGN FOR TEXTILE FABRIC.

No. 37,704.

Specification for Design.

Patented Nov. 28, 1905.

Application filed October 17, 1905. Serial No. 283,185. Term of patent 7 years.

To all whom it may concern:

Be it known that I, JOHN FREDERICK CHRISTIAN DEHLE, a citizen of the United States, residing at Sacramento, in the county of Sacramento and State of California, have invented a new, original, and ornamental Design for Textile Fabrics, of which the following is a specification.

The figure is a plan view of a textile fabric, showing my new design.

I claim—

The ornamental design for a textile fabric, as shown.

JOHN FREDERICK CHRISTIAN DEHLE.
